US0D1045626S

(12) **United States Design Patent** (10) **Patent No.:** **US D1,045,626 S**
(45) **Date of Patent:** **** Oct. 8, 2024**

(54) **WATCH**

(71) Applicant: **RICHEMONT INTERNATIONAL SA**, Villars-sur-Glane (CH)

(72) Inventor: **Julie Dicks**, Pringy (FR)

(73) Assignee: **RICHEMONT INTERNATIONAL SA**, Villars-sur-Glane (CH)

(**) Term: **15 Years**

(21) Appl. No.: **29/836,691**

(22) Filed: **Apr. 28, 2022**

(30) **Foreign Application Priority Data**

Mar. 11, 2022 (WO) WIPO114634

(51) **LOC (14) Cl.** **10-02**
